UNITED STATES PATENT OFFICE.

FRANK C. LEAHY AND GEORGE H. HILEMAN, OF DETROIT, MICHIGAN.

ANTISEPTIC CONTAINER.

Application filed December 9, 1921. Serial No. 521,221.

To all whom it may concern:

Be it known that we, FRANK C. LEAHY and GEORGE H. HILEMAN, citizens of the United States, residing at Detroit, county 5 of Wayne, State of Michigan, have invented a certain new and useful Improvement in Antiseptic Containers, and declare the following to be a full, clear, and exact description of the same, such as will enable others 10 skilled in the art to which it pertains to make and use the same, reference being had to the accompanying drawings, which form a part of this specification.

Our invention relates to an antiseptic container for brushes and combs and is particularly intended for the use of barbers.

An object is to provide a container having a brush and comb supporting means within which container a sterilizing atmosphere is 20 created through the use of a suitable volatile sterilizing compound which container is simple and inexpensive, easy of access to insert articles therein or remove the same therefrom and which is capable of being easily 25 cleansed.

A further object is the provision of a container of the class described having a removable rack adapted to support a plurality of combs and brushes around a suitably supported container provided to receive a disinfectant compound. A further object is the provision of such an article of merchandise in which the brush supporting rack may be removed from the container, and the container 30 provided to receive a disinfectant compound which in turn is supported by a rack may likewise be removed.

These and other objects together with details of construction will more fully appear 40 from the following description, claims and accompanying drawings, in which:

Figure 1 is a perspective of the supporting rack.

Fig. 2 is a section through the container 45 showing the rack partly in section and partly in elevation.

In the drawings, let 5 indicate a suitable container which might well be in the form of a cylindrical glass vessel of conventional 50 construction provided with a removable

glass cover plate 6 which is suitably supported and hinged to the vessel by means of a wire frame 7. A suitable rubber gasket is provided which fits over the top of the glass jar and upon which the cover rests. 55 The container is not air tight, however, it is sufficiently so for all commercial purposes so that the sterilizing atmosphere produced therein by the evaporation of the sterilizing composition serves to disinfect the brushes 60 and combs disposed within the container.

We provide a supporting rack indicated in assembly as 9 which is adapted to be removably received within the container 5. This rack is provided with supporting standards 65 10 formed of resilient metal so that they may be compressed to permit removal of the rack from the container and will spread outwardly against the wall of the container 70 when the rack is seated therein.

This rack is provided with a plurality of brush and comb receiving pockets 11 shaped as shown in the drawing so as to receive a comb or the handle of a hair brush which pockets are arranged in such a manner as to 75 surround the sterilizing container provided to receive the disinfectant compound which container is likewise carried by the rack.

The rack is so formed as to provide a centrally positioned frame 13 which is adapted 80 to support a removable container 14 adapted to contain a disinfectant compound. When it is desired to clean the separate parts of the receptacle, the supporting rack may be removed from the container and the container 85 vessel removed from the supporting rack. It is apparent, therefore, that the separate members may be easily cleansed.

What we claim is:

1. In a sanitary receptacle for combs and brushes, a container having a removable cover, a rack adapted to be removably received within said container so formed as to provide a plurality of brush and comb receiving pockets arranged around a centrally positioned support for a removable vessel, and a vessel adapted to contain a disinfectant compound removably carried by said support.
2. In a sanitary receptacle for combs and 100

brushes, a container having a removable cover, a rack adapted to be removably received within said container having a plurality of brush and comb receiving pockets, 5 said rack having legs of such a character as to be compressible inwardly but adapted to spread outwardly against the circumferen-

tial wall of the container when the rack is disposed therein.

In testimony whereof, we sign this specification.

FRANK C. LEAHY.
GEORGE H. HILEMAN.
